M. F. HEALY,

LIFTING DOG,

APPLICATION FILED JULY 19, 1919.

Patented Sept. 14, 1920.

FIG. 1.

FIG. 2.

FIG. 3.

INVENTOR

Maurice F. Healy

UNITED STATES PATENT OFFICE.

MAURICE F. HEALY, OF WATERTOWN, MASSACHUSETTS.

LIFTING-DOG.

1,352,665.

Specification of Letters Patent. Patented Sept. 14, 1920.

Application filed July 19, 1919. Serial No. 312,088.

(FILED UNDER THE ACT OF MARCH 3, 1883, 22 STAT. L., 625.)

To all whom it may concern:

Be it known that I, MAURICE F. HEALY, a citizen of the United States, and a resident of Watertown, county of Middlesex, State of Massachusetts, have invented an Improvement in Lifting-Dogs, of which the following is a specification.

The invention described herein may be used by the Government, or any of its officers or employees in prosecution of work for the Government, or by any other person in the United States, without payment of any royalty thereon.

This invention relates to improvements in lifting dogs or to devices known in the art as "lewises." The device is used in lifting heavy bodies by inserting it into a cavity in the body to be lifted, said device being held therein by friction or otherwise due to the expansion of its parts within the cavity.

The construction of the lifting dog here shown is especially adapted for use in lifting projectiles or other heavy bodies having 25 tapering or bottle-neck cavities, the outer extremity of which is screw threaded or is otherwise liable to injury if brought into contact with steel or other hard substance.

The object is to provide a simple, durable 30 and inexpensive device of the class described in which convenient means are provided for the insertion of the device in its collapsed form into the cavity of the body to be lifted.

Another object is to provide convenient 35 means for collapsing the parts and removal of the device from the cavity after the lifting operation has been performed.

Another object is to provide against any 40 injury to the screw threads or other destructible surface at the entrance to the cavity. To that end a structure is provided wherein the expanding or adjustable parts coming in contact with the walls of the cavity are 45 located entirely within the cavity and remote from the entrance thereof, thus avoiding any breakage, chipping or other damage near the cavity entrance. This feature is of special importance in lifting stone or other 50 fragile bodies as well as projectiles having screw threads at the entrance to the cavity.

A preferred embodiment of the improved

device is shown in the accompanying drawing in which similar numerals indicate corresponding parts in all the figures.

55

Figure 1 is an elevation of the lifting dog shown in its collapsed or non-engaging position in the end of a projectile.

Fig. 2 is a similar view with the parts expanded and in contact with the interior 60 walls of the projectile, or in their lifting position.

Fig. 3 is a top plan view of the sleeve and the parts mounted thereon.

Referring to the drawings by numerals, 65 the device consists of the hanger or lifting rod 10 having the cone or spreader 11 mounted at its lower end and the sleeve or collar 12 on which are mounted the jaws or arms 13.

70

The lifting rod 10 is preferably formed with an eye head 14 at its upper end or other suitable means for the reception of the ring 15, which ring is adapted for connection with the lifting cable of a hoisting 75 means not shown. The lower end of the rod 10 is screw threaded at 16 to receive nut 17, which locks the cone or spreader 11 on the rod. The rod 10 may be taken from stock of the proper diameter, cut into 80 lengths, threaded at one end and flattened and punched at the other, when it will be ready for use; all of which may be performed by unskilled labor.

The cone or spreader 11 is provided with 85 the bore 18 and inclined outer surface 19, and said cone is threaded on rod 10 and is firmly held in place by lock nut 17. The cone is, however, rotatably adjustable in relation to the arms 13 which are adapted to contact 90 with its upper face, thus prolonging the life of this part of the device by distributing the wear over the entire surface of the cone. The cone 11 may be cast ready for use.

The sleeve or collar 12, is provided with a 95 central bore 20 in which rod 10 loosely fits. The sleeve is preferably cylindrical and of a diameter considerably less than the dimensions of the cavity into which it is to be inserted. In the outer face of the sleeve 12, 100 are arranged a series of longitudinal dovetail grooves 21, in which preferably wooden strips 22 are inserted and project beyond the surface of the sleeve to such an extent as to

come in contact with an outer or encircling body and prevent any contact between said outer body and the sleeve.

- Near its upper edge the sleeve is provided with radial openings 23, preferably three in number, spaced uniformly about its periphery in which rods 24 have a driving fit. The rods 24 which may be stock cut to length have dual functions, one being to provide handles whereby the device may be inserted into or removed from the cavity in the body to be lifted, the other to rest on the upper edge of the cavity and suspend the device in the desired position within the cavity.

From the lower face of the sleeve 12, depending ears 25 extend, and pivotally mounted on said ears are opposed arms or jaws 13.

- The sleeve which may be cast ready for use, as above stated is rotatable on rod 10 and thus prevents localization of wear on said rod, in its bore or on the outer surface of the strips carried by the sleeve.
- The arms 13 are somewhat wider than the ears 25 and are solid throughout with the exception of the upper bifurcated end, which provides wings or projections 26 lying on opposite sides of the ears 25 and to which the arms are pivotally secured by bolts 27 passing through openings in the ears 25 and wings 26.

By mounting the arms in the manner described, the normal position of said arms when suspended on their pivots 27, is hanging directly down therefrom or in a vertical position. As shown in Fig. 1, said arms when collapsed are well within the outer dimensions of the sleeve and will freely enter any opening into which the sleeve will pass.

The lower ends of the arms 13 which may be cast ready for use are tapered on four surfaces. The inclined or tapered surface 28 is adapted for contact with the surface 19 of the cone to facilitate the spreading of the arms. The outer tapered surface 29 is provided to increase the contacting surfaces between the arms and the walls of the cavity, and, therefore, the friction between the parts and the lifting capacity of the device. The rounded or tapered edges of the arms as shown at 30 are to prevent scoring the internal face of the cavity and to prevent a surface for contact with the walls of the cavity that would not be as liable to fracture as the sharp point presented if said edges were not rounded. The tapers 30 above described also present a more uniform contact or bite between the arms and the different size cavities in which the device is intended for use.

Referring to Fig. 2 wherein the parts are shown in the lifting position, it is seen that the portion of the arm below the dotted

line or all of that portion between the cone and body to be lifted, is solid and the entire load carried by the transfer of stress in a crushing direction on said solid portion of the arms. By said construction the bolts 27 at the upper ends of the arms are almost entirely relieved of any strain, there being only a slight outward and upward stress thereon.

By the above construction approximately the entire load is carried on a tensile stress on the rod 10 and a crushing stress at right angles and through solid metal including the solid portion of the arms 13 and the cone which is thereby caused to grip the rod 10 and partly relieve the screw threads and diminish the tendency to pull the rod out of the cone by stripping the threads.

The operation will be clear by reference to the parts shown in Fig. 1 of the drawings, wherein the device is supported by the rods 24 resting at the mouth of the cavity.

By grasping the handle or rods 24, the device is suspended in a collapsed position and may be inserted into or withdrawn from the cavity. After the device has been inserted into the cavity as in Fig. 1, and lifted by the ring 15 or rod 10, the arms 13 will be spread by cone 11 as in Fig. 2 and the projectile lifted. By lifting the device by the handles 24 or sleeve 12, the arms will be withdrawn or allowed to drop into a vertical position below the bolts and the device may be readily removed from the cavity.

Having described my invention, what I claim as new and desire to secure by Letters Patent, is:

1. A lewis, including a lifting rod, a spreader on the lower end of the rod, an elongated sleeve loosely mounted on the rod and slidable longitudinally thereof, means carried by the sleeve for suspending the same in the mouth of a cavity, and arms connected to the lower end of the sleeve and actuated by the spreader to engage the walls of the cavity.

2. A lewis having a lifting rod, a cone shaped spreader threaded on the lower end of the rod and rigidly locked thereon, a sleeve loosely mounted on the rod and means for contact with the walls of the cavity supported on the sleeve.

3. A lewis having a lifting rod, a spreader, a sleeve having a padded surface loosely mounted on the rod and arms for contact with the walls of a cavity supported on the sleeve.

4. A lewis having a lifting rod, a spreader, a sleeve loosely mounted on the rod having grooves in its outer face for the reception of protecting strips and means for contact with the walls of a cavity supported on the sleeve.

5. A lewis having a lifting rod, a spreader, a sleeve loosely mounted on the rod, means

for suspending the sleeve in a cavity and arms for contact with the walls of the cavity, supported on the sleeve.

6. A lewis having a lifting rod, a spreader, 5 a sleeve loosely mounted on the rod, rods radiating from the sleeve for suspending same in a cavity and arms for contact with the walls of the cavity supported on the sleeve.

7. A lewis having a lifting rod, a spreader, 10 a sleeve loosely mounted on the rod, lugs depending from the sleeve and arms for contact with the walls of a cavity supported by said lugs.

8. A lewis having a lifting rod, a spreader, 15 a sleeve loosely mounted on the rod, lugs depending from the sleeve and arms for contact with the walls of a cavity pivotally connected to the lugs.

9. A lewis having a lifting rod, a spreader, 20 a sleeve loosely mounted on the rod, lugs depending from the sleeve and arms having tapered lower ends for contact with the walls of a cavity pivotally suspended from the lugs.

MAURICE F. HEALY.
